Term of patent 14 years

(Cl. D58—12.6)

To all whom it may concern:

Be it known that I, Robert O. Wesley, a citizen of the United States of America, residing at Plymouth, in the county of Wayne and State of Michigan, have invented a new, original, and ornamental Design for a Package for a Toy Pistol, of which the following is a specification, reference being had therein to the accompanying drawing, forming a part thereof, wherein:

Figure 1 is a side elevational view showing my new design for a package for a toy pistol; and

Figure 2 is a bottom plan view of the package shown in Figure 1.

The side of the package opposite the side shown in Figure 1 of the drawing is substantially the same in appearance as the side illustrated in Figure 1. The dot and dash lines shown in both Figures 1 and 2 of the drawing indicate the part of the grip of an actual toy pistol, which projects through the slot provided in the bottom wall of the package.

The dominant feature of the design is a picture on the side of the box illustrating that portion of the pistol contained within the box and so re-

lated to the bottom of the box that the portion of the pistol projecting through the slot complements and completes the illustration.

I claim:

The ornamental design for a package for a toy pistol, substantially as shown and described.

ROBERT O. WESLEY.
